ATTORNEYS.

UNITED STATES PATENT OFFICE.

THOMAS H. OUTERBRIDGE, OF HAMILTON, BERMUDA.

HUB-LOCK.

SPECIFICATION forming part of Letters Patent No. 234,801, dated November 23, 1880.

Application filed September 3, 1880. (No model.)

To all whom it may concern:

Be it known that I, THOMAS H. OUTERBRIDGE, of Hamilton, Bermuda, have invented a new and useful Improvement in Hub-locks, of which the following is a specification.

My improvements relate to devices for securing wheels to axles, and have for their object to dispense with the screws and nuts generally used for that purpose, and to furnish a lock that shall secure the hub safely to the spindle and can be readily manipulated.

My invention consists in a locking-tumbler combined with a case that is fitted for rotation on a spindle having a collar for retaining the case, for use in connection with a hub having lugs with which the tumbler engages to retain the hub in the spindle; also, in a spring combined with the tumbler to render the locking action automatic, and in certain other details of construction, that are set forth herein-after.

In the accompanying drawings, forming part of this specification, Figure 1 is a face view of the lock as applied to a hub. Fig. 2 is a longitudinal section of the hub and lock on line *xx* of Fig. 1. Fig. 3 is an end view of the hub with the lock removed. Fig. 4 is a face view of the lock-case with the cap and tumbler removed. Fig. 5 is an elevation of the tumbler, and Fig. 6 an elevation of the cap-plate.

Similar letters of reference indicate corresponding parts.

A is the hub, fitted with a box for receiving the spindle, and B is the spindle, provided with a collar, *a*, that sits within a recess formed for it in the end of hub A. At the inner end of the hub there are lugs *b*, preferably three in number, which lugs may be formed with and project from a cap-plate secured on the hub, or they may be the ends of T-bolts that pass into or through the hub, so as to be held securely. These projecting lugs *b* are formed with apertures in a line concentric with the hub.

C is the lock-case, fitted with tumbler D, and with the cap-plate *c*, covering the tumbler. The case C is a cup-shaped casting, formed with studs *d*, to which plate *c* is secured by screws, and with apertures *e* for the

lugs *b* of the hub to pass through. The tumbler D is a slotted circular disk of a size to fit snugly within the case C, slotted to set over the studs *d*, and also formed with three slots 55 at its edge, corresponding in position with apertures *e* of case C, at the sides of which slots pins or bolts *f* are formed, for entering the apertures of lugs *b* when the tumbler is rotated. The case C, tumbler D, and cap *c* 60 are apertured to set over spindle B, so as to turn freely thereon. The tumbler D is capable of a partial rotation independently for locking and unlocking, and, if desired, the case C is fitted with a central hub or sleeve, around 65 which the tumbler is placed so as to turn thereon.

In Fig. 5 the tumbler D is shown as fitted with a spiral spring, *h*, which, when the tumbler is inserted in case C, is compressed against 70 a stud, *i*, in the case, so that the spring tends to turn the tumbler in the direction for locking. In place of a spiral spring a piece of spring-wire may be coiled in case C, as shown by dotted lines in Fig. 4, one end being caught 75 on stud *d* and the other end engaged with a pin, *k*, on the tumbler.

The cap *c* is slotted, as shown at *l* in Fig. 6, for insertion of a key to move the tumbler back in unlocking; or a pin from the tumbler 80 may project through the slot. There may also be a spring-catch attached to the inner side of case C, for engagement with a pin on the tumbler when the hub is locked, and arranged for disconnection by a key inserted through the 85 slot in cap *c*.

It will be seen that when the hub is placed on the spindle the lugs *b* pass through the case C and tumbler D, and are caught by the bolts *f* of the latter, so that the hub is held securely.

To remove the hub the tumbler will be turned back, thereby disengaging pins *f*. The cap *c* retains the tumbler in the case, and also serves to exclude dust.

The hub may be provided with the usual dust-band to extend over the lock-case.

Having thus fully described my invention, I claim as new and desire to secure by Letters Patent—

1. In hub-locks, the tumbler D, provided with pins *f* and spring *h*, combined with the

apertured case C, having stud *i*, spindle B, having collar *a*, and hub having apertured lugs *b*, substantially as and for the purposes set forth.

5 2. In hub-locks, a lock-case provided with the cap-plate *c*, secured by screws to case-studs *d*, and having apertures *e*, through

which pass the lugs *b* of hub, as and for the purpose specified.

THOS. H. OUTERBRIDGE.
